UNITED STATES PATENT OFFICE

119,382

DESIGN FOR A BABY WALKER

Charles T. De Puy, Rochester, N. Y., assignor to Trimble Nurseryland Furniture, Inc., Rochester N. Y., a corporation of New York

Application December 18, 1939 Serial No. 88,990

Term of patent 14 years

To all whom it may concern:

Be it known that I, Charles T. De Puy, a citizen of the United States of America, residing at Rochester, in the county of Monroe and State of New York, have invented a new, original, and ornamental Design for a Baby Walker, of which the following is a specification, reference being had to the accompanying drawing, forming a part thereof.

In the drawing:

The figure is a perspective view of a baby walker showing my new design.

I claim:

The ornamental design for a baby walker, as shown.

CHARLES T. DE PUY.
